HIGH-PRESSURE GASEOUS DISCHARGE
LAMP

George A. Freeman, East Orange, and Edward A. Jenkins, Fairlawn, N. J., assignors to Westinghouse Electric Corporation, East Pittsburgh, Pa., a corporation of Pennsylvania

Application August 12, 1949, Serial No. 109,902

1 Claim. (Cl. 174—50.54)

1
The present invention relates to high pressure gaseous discharge lamps and more particularly to a seal therefor between the vitreous envelope and a high current carrying leading-in conductor for the electrodes.

It is well recognized in the art that high pressure gaseous discharge lamps reach a relatively high temperature during operation which, together with a high pressure of many atmospheres, present an exceedingly difficult problem from the standpoint of maintaining an hermetic seal. In an attempt to solve this problem seals have been employed which are capable of carrying several hundred amperes of current by utilizing a number of parallel metallic strips of molybdenum foil. Seals of this type are difficult to make and exceedingly expensive because of the painstaking skill required for their fabrication.

Another attempted solution has been the use of graded seals, but this requires that one end of the seal be formed of a glass having a coefficient of expansion approximately that of the metallic leading-in conductor which is usually formed of tungsten. The objection inherent in such prior art graded seals has been that of the glass approximating the expansion of the tungsten is entirely too soft and hence will not withstand the temperature to which the lamp is subjected during operation. To overcome this latter difficulty, special high melting point glass has been developed, but which retains a coefficient of expansion approximating that of tungsten. Again, however, an objection has been found to be inherent in this type of graded seal, because the size of the graded seal makes a large cavity in the lamp which is difficult to keep at a sufficiently high temperature to prevent condensation of mercury vapor, most commonly employed as the discharge supporting medium, during operation of the lamp. Moreover, during flame working seals of this type crack too readily during fabrication of the lamp, thus increasing salvage costs.

It is accordingly an object of the present invention to provide a seal for a high pressure discharge lamp capable of carrying high current during operation which will maintain an hermetic seal without destruction at the high operating temperature of such lamp and constructed in such a way as to avoid a large cavity in which mercury might condense.

Another object of the present invention is the provision of a graded seal for high pressure discharge lamps to bring in leads of large cross-section capable of carrying high current and of

2
withstanding the high temperature to which the lamp is subjected during operation, without destruction of the seal and constructed in such a way as to avoid a large cavity in which mercury might condense.

A further object of the present invention is the provision of a short arc high pressure discharge lamp provided with a graded seal for the leading-in conductors which will withstand the high pressure and high temperature to which the lamp is subjected during operation without destruction of such seal and constructed in such a way as to avoid a large cavity in which mercury might condense.

15 Still further objects of the present invention will become obvious to those skilled in the art by reference to the accompanying drawing wherein:

Fig. 1 is an elevational view of a high pressure discharge lamp provided with hermetic seals in accordance with the present invention;

Fig. 2 is a cross-sectional view of the hermetic seal assembly of the present invention;

Fig. 3 is a cross-sectional view taken on the line III—III of Fig. 2;

20 Fig. 4 is a cross-sectional view similar to Fig. 2, but showing an intermediate fabrication step in the manufacture of the seal assembly; and

Fig. 5 is a cross-sectional view similar to Fig. 2, but showing a modification which the seal of the 25 present invention may take.

Referring now to the drawing in detail, the lamp shown in Fig. 1 comprises a vitreous envelope 5 capable of withstanding high operating temperatures, such for example, as quartz. A pair of oppositely disposed refractory metal electrodes 6 and 7, such as tungsten or the like, are secured to the leading-in and supporting conductors 8 and 9, by a refractory metal fastening collar 10. Such collar 10 may be secured to the leading-in conductor and the electrode in any suitable manner, as by a threaded connection, set screws, or by welding. As is customary in the art following exhaust of the lamp at the tip 12, it is filled with a small quantity of an inert gas, such as neon, argon, or a mixture thereof, at a pressure of about 50 mm. to facilitate the initiation of a discharge between the oppositely disposed electrodes 6 and 7.

50 In addition a small quantity of a vaporizable material, such as mercury 13, is disposed in the envelope 5 which supports the arc-discharge once the lamp reaches stabilization temperature ranging from 500° C. to 700° C., at which time the mercury will be completely vaporized and at 55 a pressure ranging between 5 and 10 atmospheres.

Since the lamp as shown in Fig. 1 is a high intensity light source, with a power input of approximately 7.5 kw., the leading-in and supporting conductors must necessarily carry a comparatively high current of many amperes and accordingly are of relatively large cross-sectional area. The leading-in conductors for the lamp as shown are thus approximately one-quarter inch in diameter and may be of molybdenum, as shown in the preferred form of Figs. 1 to 4, or of tungsten, as shown in Fig. 5.

For the purpose of forming an hermetic seal between the leading-in conductor and the quartz envelope, the seal is first formed as a preliminary assembly by providing the leading-in conductor with a glass bead 14 having a coefficient of expansion approximating that of the molybdenum rod 15, or the tungsten rod 16 of Fig. 5. The rod is then provided with a thin metallic layer of a high refractory metal, such as tungsten, platinum, thorium or molybdenum, which may be in the form of a thin split sleeve or, as shown, it may be formed of a helical wrapping of metallic foil strip 17, such as molybdenum of approximately .0005 thickness, which in either case extends for an appreciable distance along the length of the rod 15 or 16 with such wrapped foil also extending a slight distance over the surface of the glass bead 14. A vitreous sleeve 18 having an enlarged end 19, and an internal bore slightly greater than the diameter of the wrapped rod, is then slipped over the latter, as shown in Fig. 4. It will be noted that such sleeve 18 is formed of a plurality of glass sections having a graded coefficient of expansion as is well known in the art, with the upper section 20 as shown being of the same composition as the relatively soft glass bead 14, while the lowermost section 22 is formed of a harder glass which has a coefficient of expansion approximating that of the quartz end portion 19.

The glass sleeve 18, or specifically the uppermost glass section 20 of the graded seal, is first sealed by flame working to the glass bead 14 which is of a softer vitreous material than the envelope 5 and, since a few turns of the metallic foil 17 slightly overlaps the bead 14, the end of the metallic foil is thus completely embedded in the fused mass of solid relatively soft glass, as can be observed from the completed seal assembly as shown in Figs. 2 and 5. The glass sleeve is then connected at its enlarged end 19 to a vacuum pump and after evacuation is tipped-off from the pump, as shown at the tip 24 of the enlarged end 19 in Fig. 5. Following such exhaust of the assembly, the sleeve 18 is heated by a sealing flame until the wall thereof, together with its integral graded seal, is shrunk down to the metallic foil strip 17, as can be again observed from the finished seal assembly of Figs. 2 and 5. Such shrinking causes the sleeve 18 and its graded seal to wet and adhere to the metallic foil strip 17 which being of very thin cross-section, as previously mentioned, will yield slightly thus avoiding production of destructive strains and forming a graded hard glass buffering seal.

Moreover, the leading-in conducting rods 8 and 9 can move slightly under the foil wrapping 17 to accommodate differences in thermal expansion between the rod and the quartz and seal glasses, without imposing a destructive strain upon the latter. Since the foil 17 extends to slightly overlap the glass bead 14 to which the uppermost glass section 20 is fused, as above

5 noted, an hermetic seal is thus formed at such fused juncture which is devoid of any sharp crevice that would otherwise be conducive of a slight strain causing cracking of the seal at such point.

In addition, the formation of a cavity in the seal, where at low temperature mercury vapor would otherwise condense, is effectively eliminated due to the close adherence of the shrunken glass sleeve and graded seal to the metallic foil strip 17 and the latter to the leading-in conductors 8 and 9, for substantially the entire length of the shrunken sleeve and graded seal.

Following such shrinking of the glass sleeve 15 and graded seal, the flanged end 19 of the seal assembly is cut at its enlarged end leaving a peripheral edge 25 as shown in Fig. 2. The electrodes 6 and 7, respectively, are then secured by means of the collar 10 to the end of the leading-in conductors or rods 8 and 9, thus completing the preliminary seal assembly. The latter is then ready for fusing at the peripheral edge 25 of the flanged portion 19 to an annular vitreous collar or extension on the bulbous envelope 5, 25 thus forming a juncture 23 which is hardly observable in the finished lamp of Fig. 1. The lamp is then completed in the customary manner by again evacuating, filling with a small quantity of a monatomic starting gas, such as 30 argon, neon or a mixture thereof, and a small quantity of a vaporizable material, such as mercury, in an amount which becomes completely vaporized during operation and the lamp finally sealed off.

35 The modification as shown in Fig. 5 differs from that shown in the remaining figures, not only in that the leading-in conducting rod is shown as formed of tungsten with a glass bead 14 and uppermost section 17 of a glass having 40 a coefficient of expansion approximating that of the tungsten, in lieu of the molybdenum rod of Fig. 2 and its sealing glass bead 14, but the entire seal of this modification is of reduced length by utilizing recently developed higher melting 45 point glass compositions. However, the higher melting point sealing glasses are much more difficult to work and since more skill is required, it is more desirable to employ the softer glass graded seals, as shown in the preferred embodiment of Figs. 1 to 4, inclusive. Of course, in instances where the leading-in rod is of molybdenum, the seal may also be of shorter length when desired by employing the higher melting point sealing glasses, so long as the thermal expansion of beading glass 14 matches that of the metallic rod, whether it be tungsten, molybdenum or other refractory metal.

It thus becomes obvious to those skilled in the art that a high pressure gaseous discharge is 60 herein shown and described capable of passing high current and which is provided with an hermetic seal which will withstand the high operating temperatures without destruction over the entire useful life of the lamp.

65 Although several specific embodiments of the present invention have been shown and described, it will be understood that still further modifications thereof may be made without departure from the spirit and scope of the appended claim.

We claim:

An hermetic electrically conducting seal for an electrical discharge lamp comprising an elongated rod like molybdenum leading-in and supporting conductor carrying an electrode at one end thereof, a thin spiral wrapping of molybde-

num ribbon surrounding said leading-in and supporting conductor and firmly engaging the surface thereof throughout substantially its entire length within the lamp, and a vitreous sleeve including a graded portion formed of a plurality of vitreous sections having a graded coefficient of expansion and fused at one end of said sleeve to said leading-in conductor at a point remote from the electrode carrying end and embedding one end of said metallic wrapping in the fused mass, and said graded portion of said vitreous sleeve extending a substantial distance longitudinally of said leading-in conductor and being shrunken down into wetted engagement with said wrapping substantially throughout its length, to form a graded buffering seal and to effectively eliminate the formation of a cavity in the seal.
